UNITED STATES PATENT OFFICE.

LEA SCOTT, OF CAMDEN, NEW JERSEY.

DESIGN FOR A BRUSH-BRIDLE AND BROOM-HEAD.

SPECIFICATION forming part of Design No. 32,670, dated May 15, 1900.

Application filed April 9, 1900. Serial No. 12,254. Term of patent 14 years.

To all whom it may concern:

Be it known that I, LEA SCOTT, a citizen of the United States, residing in the city and county of Camden, State of New Jersey, have 5 invented and produced a new and original Design for a Brush-Bridle and Broom-Head, of which the following is a specification, reference being had to the accompanying drawing, forming part thereof.

10 The leading feature of my design for a brush-bridle and broom-head is a skeleton frame consisting of a top ring, side arms pendant therefrom, and a bottom band continuous of the lower end of one of the arms and joining the lower end of the other arm.

15 The figure represents a perspective view of a brush-bridle and broom-head embodying my design.

In the drawing, A designates a bridle and head composed of the ring B, the spiral side 20 arms C C, the eye D of the lower end of one of the side arms, and the band E, which extends horizontally from the lower end of the other side arm and joins said eye D.

Having thus described my invention, what 25 I claim as new, and desire to secure by Letters Patent, is—

The design for a brush-bridle and broom-head substantially as shown and described.

LEA SCOTT.
